UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

ELECTRIC SEMAPHORE MECHANISM.

1,056,992.

Specification of Letters Patent. Patented Mar. 25, 1913.

Application filed December 3, 1909. Serial No. 531,264.

To all whom it may concern:

Be it known that I, WINTHROP K. HOWE, a citizen of the United States, and resident of Rochester, in the county of Monroe and State of New York, have invented certain new and useful Improvements in Electric Semaphore Mechanisms, of which the following is a specification.

This invention relates to electric semaphore mechanism of the type in which a semaphore having a bias to danger position is moved from such position to a set position, giving a cautionary or safety indication, by means of a rotary electric motor 10 geared to the semaphore, and in which the semaphore is held in such set position by an electrically-controlled detent, the motor being deenergized to economize the electric current while the signal is so held.

20 The object of the invention is to produce a mechanism, of the kind in question, in which the signal may be powerfully and quickly moved in both directions of operation, but in which shock and jar are avoided 25 when the signal is brought to rest, after such movement, in either danger position or set position.

To accomplish the foregoing object I employ a novel arrangement of the detent 30 mechanism and of the circuit-controller by which the action of the detent is controlled, together with certain yielding devices interposed between several parts of the semaphore mechanism, and I will describe these 35 devices in connection with the description of the illustrated embodiment of the invention, the essential features of the invention being defined in the succeeding claims.

In the accompanying drawings:—Figure 40 1 is a side-elevation of a semaphore and its actuating-mechanism embodying the present invention, the actuating-mechanism being shown partly in vertical section; Fig. 2 is a rear-elevation of the semaphore actuating-mechanism; and Fig. 3 is a diagram illustrating the electrical connections between the several parts of the mechanism.

The illustrated embodiment of the invention comprises a semaphore having the usual 50 arm 4 supported by a spectacle-casting 5. These parts may be of any ordinary or suitable form, and the semaphore is illustrated as of the lower-quadrant type, that is to say, the arm, when in clear or set position, is 55 downwardly inclined, as shown in Fig. 2,

while its horizontal position gives a danger indication. The semaphore-arm assumes such horizontal position automatically in response to its gravitational bias, as is common in such mechanisms.

60 The semaphore is mounted upon the usual horizontal semaphore-shaft 6 which is journaled in a bearing on a plate 7. The spectacle-casting and plate 7 are provided, in the usual manner, with stop-lugs 8 which limit the movements of the semaphore in both danger position and clear position.

The semaphore is moved from danger position to set position by means of an electric motor of any ordinary or suitable form, this 70 motor being illustrated as provided with an armature 9-mounted on a shaft 10. The armature-shaft is provided with a pinion 11, which is loose upon the shaft but is held to rotate therewith by a frictional device. 75 This device comprises a spring-pressed collar 12 which presses the pinion against a collar on the right-hand end of the shaft, as shown in Fig. 1, and thus, except when subjected to excessive strains, the pinion rotates 80 with the armature-shaft and communicates power from the motor to the semaphore to move the latter.

The pinion 11 meshes with a gear 13 which is journaled upon the reduced extremity 14 of the semaphore-shaft 6. Integral with the gear 13 is a pinion 15 which meshes with a gear 16. The gear 16 is journaled upon a stud 17 fixed in the casing 18 of the mechanism. A pinion 19 is also 90 journaled loosely upon the stud 17, and this pinion is connected with the gear 16 by means of a ratchet-and-pawl mechanism 20, this mechanism being arranged, as shown in Fig. 1, so that when the motor operates 95 the gear 16 rotates the pinion 19 through the ratchet-and-pawl mechanism, while this mechanism permits the gear 16 to rotate in the opposite direction while the pinion 19 is at rest, for a purpose which will be 100 presently described.

The pinion 19 engages a segmental gear 21 which is fixed on the semaphore-shaft, and the operation of the gearing just described, as a whole, is such that when the 105 motor is energized it acts to turn the semaphore-shaft and swing the semaphore-arm downward from horizontal danger position to inclined set position, in opposition to the bias of the semaphore.

110

The electrically-controlled detent-mechanism by which the semaphore is held in set position is illustrated particularly in Fig. 2. Upon the rear-end of the armature-shaft 10 is mounted a detent-plate 52 which is provided with a series of three radial teeth or abutments. Upon a fixed portion of the apparatus is mounted a plate 22 having a horizontal ledge or abutment, and above this ledge are two anti-friction rollers 23 constituting a detent adapted to coöperate with the fixed abutment and the abutments on the plate 52. When the rollers are interposed between these abutments, as in Fig. 15 2, reverse rotation of the motor-shaft is prevented and the semaphore is held in set position, but when the rollers are moved to the left, so as to disengage the abutment on the detent-plate 52, the latter can rotate 20 to permit the semaphore to return to danger position in response to its bias.

The detent-rollers 23 are moved into and out of operative position by means of upwardly-projecting arms 24 fixed on a sleeve 25 which is journaled on a pin 25 in the motor-casing. The rollers have gudgeons engaging vertical slots in the arms, as shown in Fig. 2. A weight 26 on an arm projecting from the sleeve tends constantly to throw 30 the detent into operative position. Another arm 27 projecting horizontally from the sleeve is normally engaged by a vertically-movable magnetic core 28, and the weight of this core is sufficient to hold the detent 35 in inoperative position against the action of the weight 26. The core is controlled by a solenoid 29 through which it moves, and when the solenoid is energized the core is raised so as to release the arm 27 and permit 40 the weight 26 to throw the detent into operation.

The detent-mechanism just briefly described is more fully disclosed and claimed in United States Letters Patent granted to me February 28, 1911, No. 985,677, relating to detent-mechanism, which is a division of the present application, and it is not, therefore, particularly described and claimed herein. An important feature, however, of 50 the present invention resides in the use of a yielding connection between the detent-plate 52 and the motor-shaft. To this end the plate is journaled loosely on the shaft, but it rests against a friction-collar 30 fixed 55 on the shaft (Fig. 1) and is pressed against this collar by means of a spring-pressed collar 31 slidingly mounted on the shaft. By this arrangement the shaft is prevented from rotating freely when the detent is in 60 operation, but opportunity is afforded for a slight yielding movement of the shaft when the detent is first thrown into operation, as will be presently described.

The illustrated semaphore-mechanism is 65 provided, as is usual in such devices, with

a circuit-controller moved in accordance with the movements of the semaphore and operating to control the circuits through the motor and the detent-mechanism. This circuit-controller, as illustrated, comprises a drum 33 of insulating material carrying the movable contacts of the controller, and stationary insulating supports 34 upon which the fixed contact-springs are mounted. The drum 33 is mounted upon, and actuated by, a rock-shaft 35 journaled in the frame of the mechanism, and this shaft is provided with a segmental gear 36 meshing with a segmental gear 37 fixed on the rear extremity 14 of the semaphore-shaft.

The circuit through which the motor is energized is controlled by a contact-strip 38 on the drum 33 coöperating with two contact-springs 39 and 40. The operation of these parts is, or may be, the same as in previous well-known constructions. Referring to Fig. 3, a battery 41 is indicated diagrammatically as a source of current by which the semaphore-mechanism is energized through a controlling-circuit extending to a track-relay or other controlling device. Such a device is indicated diagrammatically at 42 as a simple circuit-closer. This circuit-closer is connected with the battery by a wire 43, and from the fixed contact of the circuit-closer a wire 44 extends to the contact-spring 40. When the circuit is closed current flows from the battery to the contact-spring 40, and if the semaphore is in danger position this contact-spring is engaged by the contact-strip 38 and the current flows to the contact-spring 39 and thence, through a wire 45, to the motor. From the motor the current returns, through a wire 46, to the battery. The detent-mechanism is controlled by a shunt-circuit also energized by the battery 41. To this end a contact-spring 47 is connected with the wire 44, and a second contact-spring 49 is connected by a wire 50, with the solenoid 29. The portion of the circuit just described is controlled by a contact-strip 48 on the drum 33. When this strip engages the springs 47 and 49 a portion of the current in the wire 44 flows through these parts and through the solenoid, and returns thence, through a wire 51, to the wire 46 and the battery.

An important feature of the invention resides in the construction and relation of the contact-strip 48 and the springs 47 and 49. This contact-strip is of such length and so placed upon the drum that it engages the springs 47 and 49 when the semaphore is in its set position, but when the semaphore is slightly beyond such position, that is to say, in a more inclined position, the contact-strip moves beyond and disengages the spring 49, thereby opening the circuit through the detent-solenoid.

The operation of the apparatus as a whole will now be described.

With the semaphore in normal danger position, suppose the circuit is closed by the circuit-closer 42. Current now flows through the wire 44, the contact-spring 40, the contact-strip 38, the spring 39, the wire 45, the motor and the wire 46, and the motor immediately operates and moves the semaphore from horizontal position toward the position of Figs. 2 and 3. At this time the pawl-and-ratchet mechanism 20 is in operation to cause the gear 16 to rotate the pinion 19, as before described. As the movement just described continues, the contact-strip 48 comes into operative position, while at the same time the contact-strip 38 moves entirely beyond and disengages the spring 40 when the semaphore has reached set position. Owing, however, to the momentum of the semaphore it does not immediately come to rest, but moves freely a short distance beyond set position, until its momentum is absorbed by its gravitational bias, or until the stops 8 come into operation. The semaphore, although moved rapidly to set position, is thus permitted to come to rest, or substantially to rest, without shock or jar. During this short overrun movement the contact-strip 48 moves beyond and disengages the contact-spring 47, as before described, so that at this time the detent is inoperative. Accordingly, the semaphore is free to return from its overrun position to the predetermined set position, but when this return movement has occurred the contact-strip 48 again engages the spring 47, thereby closing the circuit through the detent-solenoid. The detent now operates and arrests the semaphore in its return movement. At this time the frictional connection between the detent and the motor-shaft performs its function, as it permits a slight yielding whereby the momentum of the semaphore and of the motor-armature is absorbed without shock or jar. When the controlling-circuit of the semaphore is again broken by the circuit-closer 42 the detent-solenoid is deenergized and the detent moves to inoperative position, thereby releasing the motor-shaft. The semaphore then returns to danger position in response to its bias, causing the motor-shaft and the armature to rotate in a reverse direction. This return movement of the semaphore is finally arrested by the stops 8 when the semaphore has reached danger position. At this time the motor-armature is in rapid rotation, and the pawl-and-ratchet mechanism now comes into useful operation since it permits the motor-shaft to continue to rotate reversely until this momentum is spent, after the semaphore has been arrested, as just described, in danger position.

65 The friction-coupling between the motor-

shaft and the pinion 11 is for the purpose of preventing shock to the mechanism in case the semaphore, in moving to and beyond set position, is arrested by the engagement of the stops 8 before its momentum has been absorbed during its overrun movement previously described. This friction connection acts at such time to permit the motor-armature, which is in rapid rotation, to continue rotating, after the semaphore has been so arrested, until the momentum of the armature is absorbed by the friction.

70 It will be apparent from the foregoing description that the several electrical and mechanical devices hereinbefore described co-operate in such a manner that while the movements of the semaphore may be rapid and positive, such movements terminate at all points without shock or jar to the mechanism, and thus the danger of breakage or 75 excessive wear on the mechanism is eliminated.

80 My invention is not limited to the details of construction and operation of the illustrated embodiment thereof, but may be embodied in various other forms within the 85 nature of the invention as it is defined in the following claims.

90 What I claim is:—

95 1. Signal mechanism having, in combination, a signal having a normal position and a set position, the signal being movable from normal position to and beyond set position and having a bias toward normal position, electrically-controlled means for holding the signal in set position in opposition to said bias, a source of current for energizing said means, a circuit-controller connected with, and movable in accordance with, the signal; the holding means, the source of 100 current and the circuit-controller being connected in circuit, and the circuit-controller having cooperating contacts arranged to control the flow of current in said circuit so as to throw the holding means out of operation 105 when the signal moves beyond set position and to throw the holding means into operation when the signal returns thereafter to set position in response to its bias.

110 2. Signal mechanism having, in combination, a signal having a normal position and a set position, the signal being movable from normal position to and beyond set position and having a bias toward normal position, mechanism for holding the signal in set position in opposition to said bias, a magnet for controlling said mechanism, the mechanism being operative when the magnet is energized and inoperative when the magnet is deenergized, a source of current, a circuit-controller connected in series with the magnet, and connections between the circuit-controller and the signal whereby the circuit-controller is moved in accordance with 115 the movements of the signal; the circuit- 120

- controller having coöperating contacts arranged to open said circuit when the signal moves beyond set position and to hold it open until the signal returns to set position 5 in response to its bias, so as to prevent operation of the holding mechanism when the signal is beyond set position.
3. Signal mechanism having, in combination, a signal having a normal position and 10 a set position, the signal being movable from normal position to and beyond set position and having a bias toward normal position, means for arresting return movement of the signal, in response to said bias, 15 in set position, means for arresting return movement of the signal in response to said bias in normal position, a motor for moving the signal from normal position to set position, and mechanical connections between 20 the signal, the motor and the first named arresting means, said connections including yielding devices adapted to permit the motor to continue to move, in consequence of its momentum, after either of said arresting 25 means has come into operation, so that the motor may come gradually to rest in either position of the semaphore.
4. Signal mechanism having, in combination, a signal having a normal position and 30 a set position, the signal being movable from normal position to and beyond set position and having a bias toward normal position; signal-controlling mechanism connected with the signal and including a motor for moving the signal to set position, and detent mechanism arranged to operate when the signal, after having moved through its momentum beyond set position, returns in response to its bias to set position, thereby 35 arresting the signal in set position, the signal-controlling mechanism including also yielding devices between the signal and the detent, adapted to yield when the detent operates, to avoid excessive shock to the 40 mechanism.
5. Signal mechanism having, in combination, a signal having a normal position and a set position, the signal being movable from normal position to and beyond set position and having a bias toward normal position; signal-controlling mechanism connected with the signal and including a motor for moving the signal to set position, and a detent for arresting movement of the signal when the latter, after it has 45 moved beyond set position, returns in response to its bias to set position; electromagnetic mechanism for controlling the detent; a source of current and a circuit-controller connected in circuit with the electromagnetic mechanism, the circuit-controller being connected with the signal so as to move in accordance therewith and having coöperating contacts arranged to control the flow of current through said electromagnetic mechanism so as to throw the detent into operation at the time hereinbefore specified, said signal-controlling mechanism including yielding devices, between the detent and the signal, adapted to yield 50 when the detent operates, so as to avoid excessive shock to the mechanism.
6. Signal mechanism having, in combination, a signal having a normal position and a set position, the signal being movable from normal position to and beyond set position and having a bias toward normal position, signal-controlling mechanism connected with the signal and including a motor for moving the signal to set position, and detent mechanism for arresting the signal-controlling mechanism when the signal is in set position, the detent mechanism including yielding devices to permit the motor to come gradually to rest when the detent operates. 55
